UNITED STATES PATENT OFFICE.

JOHN F. BOWDITCH, OF BOSTON, MASSACHUSETTS.

PACKAGE.

981,744.

Specification of Letters Patent. Patented Jan. 17, 1911.

Application filed March 19, 1910. Serial No. 550,445.

To all whom it may concern:

Be it known that I, JOHN F. BOWDITCH, of Boston, in the county of Suffolk and State of Massachusetts, have invented certain new and useful Improvements in Packages, of which the following is a specification.

This invention relates to means for packaging powdered or granular material in such form that it can be conveniently discharged 10 in limited quantities, and preferably so that the material may be scattered as it is used.

The object of the invention is to provide a cheap and convenient holder for the powder or granular material so that the holder and 15 its contents may be sold as a package ready for the contents to be gradually used up, after which the holder may be discarded.

To these ends the invention consists in a holder or package substantially as herein- 20 after described and claimed.

In the accompanying drawings—Figure 1 is a perspective view of a holder constructed according to my invention. Fig. 2 represents a longitudinal section through the 25 holder and powder or granular material contained therein. Fig. 3 is a perspective view of one of the slides or partitions.

Similar reference characters indicate the same or similar parts in all of the figures.

30 An elongated container 10 which is preferably in the form of a tube, has a permanently closed end 11, and a series of slits 12 at substantially equal distances from each other. These slits are usually too narrow to 35 permit of the escape of the material in the container 10 even if the partitions herein-after referred to are removed.

Extending transverse of the container are 40 slides or partitions 13, preferably having tabs 14 to enable the partitions to be withdrawn and reinserted if desired. The other end of the container is provided with a cap 15 which when removed, enables the container to be filled. Near the end which 45 is provided with the cap 15, there is a side opening 16 which is normally closed by a sleeve 17, said sleeve having an opening 18 which, when the sleeve is rotated so that the openings 16 and 18 are partially or 50 wholly registered, will enable the granular material to be sifted out. Preferably the sleeve 17 is held in its longitudinal position between a collar 19 and a cap 15, it being understood that the cap 15 is per- 55 manently secured in place after the container has been filled.

All of the members or parts of the device may be made of paste board. For some purposes the sleeve 17 may be left in the position shown in the drawings, and then either 60 punching holes in the cap 15 or entirely removing it, will enable the contents to be sifted out.

In filling the container, the material such as a "carpet sweeping compound" or com- 65 minuted wax for waxing floors, or bluing, is filled in to the level of the lowest slit 12 and then a slide or partition 13 is put in. After this the filling proceeds to the next slit and another partition is put in place and 70 so on until the entire tube is filled and the cap 15 put on.

Since the partitions are of paste board the tabs 14 may be folded down and covered by the advertising label which is usually 75 employed for such goods. But in this case the paper which covers the tabs should be of such material as to enable it to be readily broken to enable the user to lift up the tabs 80 of the partitions to enable the latter to be pulled out.

When the material is to be used, the upper compartment is opened in either manner described and the material sifted out 85 through the opening; i. e., all of the material which is above the upper partition can be so sifted out. This will be a definite and known quantity. No excess quantity of the material will escape from the container. 90 When it is desired that more of the material shall be used, the upper slide or partition can be wholly or entirely removed. When all of the slits are occupied by partitions, the latter can be removed successively, 95 i. e., after the material above each partition has been used, access to the contents of the next compartment can be had by simply removing the top partition which still remains above the material in the container.

If desired, only one or two partitions need 100 be used. If the granular material is too coarse to escape through the slits 12, or if the label wrapping extends entirely over the slits, the package can be used with only 105 one partition, in which case such partition is not discarded after it is first withdrawn.

Supposing there is but one slide or partition 13 and that it first occupies the uppermost position provided for by the series of slits. When the contents of the container above said partition shall have been sifted 110 out and the container turned then to an

upright position, the said partition can be inserted in the next to the top slit and utilized as a barrier to prevent the escape of more than the desired quantity of the material when the container is again inverted for sifting. Repetitions of this operation will result in the gradual use of the material, in measured quantities.

As has been stated, the device as a whole is of material so cheap that it can be entirely discarded after it has been emptied without further waste or loss than when any ordinary paste board box is thrown away.

It is to be understood that I do limit myself to the use of the holder for powdered or granular material. Obviously the compartments or chambers between the partitions are well adapted to receive single articles which are to be kept separate from each other and which then may be removed one at a time. For instance, many fruits of a choice nature can be, with advantage, packed in a holder such as is shown in Fig. 1.

I claim—

1. A packaging holder constructed to be completely filled and to retain its contents during transportation, said holder comprising a container having a series of slits in its wall and being permanently closed at one end, a removable partition occupying one of the slits and extending entirely across the container and coacting with said closed end to form a compartment to hold granular material when the holder is inverted,

and means whereby the contents of said compartment can be sifted out.

2. A packaging holder constructed to be completely filled and to retain its contents during transportation, said holder comprising an elongated container closed at one end and having a movable closure at the other end, said container having a series of slits in its wall, and a removable partition dividing the holder into compartments and adapted to be inserted through either slit whereby it may be transferred from one position to another relatively to the ends of the container, said partition coacting with the movable closure to form a compartment to hold and retain a definite quantity of material regardless of the position of the holder.

3. A holder comprising an elongated container having a series of slits in its wall, a series of removable and independent partitions transverse to the container and dividing it into compartments, portions of the partitions projecting through said slits whereby they may be removed in succession, said holder being filled with material in all its compartments, and means whereby the contents of one end compartment may be sifted out.

In testimony whereof I have affixed my signature, in presence of two witnesses.

JOHN F. BOWDITCH.
